GATE VALVE

John L. Williams, Portland, Oreg.

Application December 8, 1955, Serial No. 39,240

Term of patent 14 years

(Cl. D78—1)

FIG.1

FIG. 2

FIG. 3

FIG. 4

Fig. 1 is an end view of the gate valve;
Fig. 2 is a side view of the gate valve;
Fig. 3 is a top view of the gate valve; and
Fig. 4 is an enlarged sectional view through one of
the yoke arms of the gate valve taken substantially along
line 4—4 of Fig. 1.

I claim:

The ornamental design for a gate valve, as shown.
